UNITED STATES PATENT OFFICE.

ROY E. CORAM, OF NEWARK, NEW JERSEY, ASSIGNOR TO WESTERN ELECTRIC COMPANY, INCORPORATED, OF NEW YORK, N. Y., A CORPORATION OF NEW YORK.

SECRET SIGNALING.

Application filed November 21, 1923. Serial No. 676,031.

This invention relates to secret signaling and particularly to the secret transmission of speech by electrical waves.

It is an object of the invention to provide 5 a simplified and highly efficient means for transmitting a signal in such a manner as to render it incapable of intelligible reception by ordinary means.

It has been proposed to obtain secrecy in 10 telephonic or other messages by confusing the message at the transmitting station and automatically recasting or untangling it at the receiving station, thus rendering it practically impossible for an unauthorized person to obtain the information contained therein. It has been proposed to accomplish this 15 by modulating high frequency carrier waves by waves within the speech frequency range in a thermionic modulator, then suppressing the original carrier and the upper side band and transmitting only the lower side band. This lower side band represents an inverse 20 frequency speech wave which may be recast into intelligible form at the receiving station by reversing the process by which the signal has been confused. It has also been proposed to vary the frequency of the carrier wave continuously and in a predetermined order to lessen the possibility of its 25 intelligible reception by an outsider. In such a system, it is important to suppress the unmodulated carrier wave component to prevent the carrier frequency, and the scheme of varying it, from becoming known, 30 and it is likewise necessary to suppress one side band of the modulated carrier wave, since if both side bands were transmitted, a simple detector would yield currents of the double frequencies of the voice which are to 35 a certain degree intelligible.

In systems of the character described, the unmodulated carrier wave and its upper side band have been eliminated quite successfully by means of filters, but another and more 45 formidable difficulty is presented which it is difficult to overcome by ordinary means, namely, since the thermionic modulator acts to a certain extent as an amplifier, the original currents of signal or speech frequencies, 50 are not entirely suppressed in the modulator and are partly passed to the line. If these currents are allowed to be transmitted, even in very small amounts, it might be possible to separate them by filters and to amplify

them to the desired degree, thus defeating the purpose of the system. In order to substantially suppress currents of speech frequencies in a thermionic modulator, a complicated and expensive system is required. This difficulty is entirely overcome by the present invention.

In accordance with a feature of the invention, a high frequency carrier wave is modulated by waves of speech frequency in such a manner as to completely suppress the original speech currents, the unmodulated carrier wave and its upper side band then being eliminated and only the lower side band passed to the line. More specifically, 70 the speech currents are completely suppressed in a simple and inexpensive electromagnetic modulator, and the unmodulated carrier wave and its upper side band are eliminated by filtering and the lower side band alone is transmitted to the receiving 75 station without distortion.

Other features and advantages of the invention will appear from the consideration of the following description taken in connection with the accompanying drawing, in which Fig. 1 shows a transmitting circuit of a system embodying the invention, and Figs. 2 and 3 illustrate modifications thereof.

Referring to Fig. 1, a microphone 1, representative of an ordinary subscriber's telephone transmitter or any other low frequency transmitting device, is connected to a speech frequency line 2. The line 2 terminates in the receiving coil 3 of a modulating device M. The modulator M comprises an electromagnetic telephone repeater which may be of the type disclosed in Patent No. 1,156,636, issued October 12, 1915 to H. E. Shreeve, the incoming voice currents actuating the repeater in the usual manner. The carrier waves are impressed on a circuit 5 including the transmitter microphone 4 of the electromagnetic modulator M by means of a high frequency carrier source 6 coupled thereto 85 by means of a transformer 7. The varying resistance of the transmitter button of the microphone 4 varies the amplitude of the carrier current which is circulated through it. This variation in amplitude results in 90 three frequencies being impressed upon the circuit 5, namely, the original carrier, the carrier plus the speech currents and the carrier minus the speech currents. The original 95 100 105

speech currents are completely suppressed in the modulator, no part of them being passed to the line. The transformer 8 connects the circuit 5 to the input of a low pass filter 9 which is thereby supplied with current of the frequency of the carrier source 6, as well as the two side bands produced by the combination or modulation of the two currents impressed upon the modulator. The low pass filter 9 may be designed in accordance with the principles set forth in Patent No. 1,227,113 issued May 22, 1917 to G. A. Campbell, and is so arranged as to pass with approximately negligible attenuation currents of frequencies lower than a fixed cut-off frequency, as for example, 3,000 cycles, and substantially extinguishes currents of higher frequencies. If, therefore, the current generated by the high frequency source 6 is approximately 3,300 cycles, it will be evident that this unmodulated carrier current as well as the side band comprising the sum-component of the original carrier and the low frequency speech currents will be suppressed by the low pass filter 9, and the filter will pass only the side band comprising the difference component of the original carrier and the speech waves. Since the resultant wave passed by the filter 9 is of a frequency equal to the original carrier minus the input speech, it is an inverse function of the speech currents, or in other words, an inverted wave, and is therefore incapable of intelligible reception by ordinary means. In practice, the inverse speech currents are transmitted over a telephone circuit to a receiving station, not shown, or they may be used to modulate a radio or carrier wave for transmission to the distant station where they are recast into intelligible form by means of a suitable demodulator. This may be accomplished by passing the incoming waves at the receiving station through a duplicate of the modulating system shown, the incoming line terminating in the receiving coil of the repeater, to restore the speech frequencies to their normal order.

A modification of the invention is shown in Fig. 2 in which a push-pull modulator circuit is used with a carrier frequency which, for ordinary purposes, may be approximately 3,000 cycles. The output of the low frequency circuit 2 is coupled by means of a transformer 10 to a filtering circuit including the low pass filter 11 so designed as to transmit freely currents of the frequencies from zero to an upper limit of preferably about 3,000 cycles, or at least sufficiently high to include the ordinary frequencies comprised within the voice range, but to suppress higher and unessential harmonics. The output of the filter 11 is connected to the receiving coil of a balanced modulator M. This modulator is similar to that described

in connection with Fig. 1 except that the microphone element 4 is of the push-pull type having two electrodes which are connected respectively to the ends of the primary of transformer 8 and a diaphragm connected through the secondary of transformer 7 to the midpoint of the primary of transformer 8. The carrier waves generated by the source 6 are thus impressed upon two balanced parallel circuits each of which include one electrode and the diaphragm of the microphone element 4, and the unmodulated carrier current is balanced out so that the current induced in the secondary of transformer 8 consists of only two frequencies, namely, the carrier plus the speech currents and the carrier minus the speech currents. This modulating circuit thus prevents the transmission of substantially all unmodulated currents, since the original speech currents are completely suppressed in the electromagnetic repeater, and the unmodulated carrier is balanced out in the balanced circuits of the modulator. The low pass filter 9, which is connected to the secondary of transformer 8, suppresses the upper side band and permits the transmission of only the lower side band. This lower side band, which is transmitted over a telephone circuit, or by modulating carrier or radio waves, to the receiving station, consists of frequencies in the voice range but which are unintelligible due to the inverted frequencies. In order to restore the speech frequencies to their normal order, it is necessary to pass the inverted speech through a duplicate of the modulating apparatus as in the case of the system described in connection with Fig. 1.

In Fig. 3, a modification of the transmission system described in connection with Fig. 2 is shown. In this system, two electromagnetic telephone repeaters are employed having their receiving coils 3 and 3' coupled to the speech frequency line 2 by means of a transformer 12 having two secondary windings. The electrodes 4 and 4' of the repeater are connected respectively to the ends of the primary of transformer 8 and their diaphragms are connected through the secondary of transformer 7 to the midpoint of the primary of transformer 8. The varying resistance of the transmitter electrodes 4 and 4' of these repeaters varies the amplitude of the carrier current generated by the source 6, this system operating in a manner similar to that shown in Fig. 2, the two repeaters taking the place of a single repeater having a push-pull transmitter. The original speech currents are completely suppressed in the electromagnetic repeater and the unmodulated carrier current is balanced out in the parallel circuits described above so that no direct speech or unmodulated carrier waves are passed to the line. The upper

side band is filtered out by the low pass filter 9 and only the lower side band is passed on to the receiving station where it is demodulated in the manner described above.

- 5 The system herein described and illustrated provides a simple and inexpensive means for completely suppressing the original speech currents and for eliminating the unmodulated carrier and one of its side 10 bands. It may also be noted that in this system any degree of modulation may be obtained depending on the constants of the electromagnetic modulators employed.

It will be understood that the invention is 15 not to be construed as limited to the actual frequency values that have been given above by way of illustration, but that frequencies higher or lower than those above assigned to source 6 may be used. So long as the resulting lower or inverse side band lies in the audio-frequency range it will be heard in an ordinary receiving circuit as noise, and will tend to confuse or mask the signal.

Although the invention has been shown 25 and described in connection with carrier secrecy systems, it will be understood that it is equally applicable to radio signaling systems. Furthermore the invention is not to be limited either in these or other respects 30 by the specific embodiments and details herein shown and described, except as defined by the scope of the appended claims.

What is claimed is:

1. In combination, a circuit including a 35 source of sustained carrier waves of a frequency at least as high as the upper essential speech frequencies, a mechanically variable resistance controlled in said circuit to modulate said carrier waves, said resistance being 40 varied to produce modulated carrier waves having a lower side band within the audio frequency range, and a filter for transmitting only said lower side band.

2. In combination, a transmission medium, 45 a circuit including a source of sustained carrier waves associated therewith, said waves having a frequency at least as high as the upper essential speech frequencies, means for modulating said carrier waves in 50 accordance with speech waves while preventing speech currents from being set up in said circuit, said modulated waves having a lower side band within the audio frequency range, and means for transmitting only the 55 lower side band within the audio frequency range.

3. In combination, a modulator circuit 60 comprising a source of sustained carrier waves of a frequency at least as high as the upper essential speech frequencies, a mechanically variable resistance in said modulator circuit adapted to be controlled in accordance with speech waves to modulate said carrier waves and to suppress speech cur- 65 rents from transmission to said modulator

circuit, and an outgoing circuit having a filter included therein for limiting the transmitted frequencies to audio frequencies lower than the frequency of said source of carrier waves.

4. A secret signaling system comprising an electromagnetic repeater having a receiving coil and a microphone element, means for circulating a current of high frequency near the upper limit of the audio frequency range through said microphone element, means for passing currents of speech frequency through said receiving coil to modulate said high frequency current, and means for suppressing the unmodulated high frequency current component and the upper side band produced by modulation and for transmitting the lower sideband within the audio-frequency range.

5. A secret signaling system comprising an electromagnetic repeater having a receiver coil and a microphone element, means for circulating a current of high frequency near the upper limit of voice frequency range through said microphone element, means for passing currents of speech frequency through said receiving coil to modulate such high frequency current without setting up speech currents in the circuit of the microphone element, and a filter adapted to suppress currents of the frequency of the unmodulated high frequency current component and the upper side band produced by modulation and to transmit only modulated currents within the voice frequency range.

6. In a secret transmission system, a push-pull electromagnetic repeater comprising a receiving coil and a microphone element having two electrodes, means for impressing a current of high frequency near the upper limit of the voice frequency range upon two balanced circuits each including one of said electrodes, means for passing currents of speech frequency through said receiving coil to modulate said high frequency current without setting up speech currents in the circuits of the two electrodes, and a low-pass filter for suppressing the unmodulated high frequency current and the upper side band.

7. In a secret transmission system, a pair of electromagnetic repeaters each having a receiving coil and a microphone element, means for impressing a current of high frequency near the upper limit of the voice frequency range upon two balanced circuits each including one of said microphone elements, said high frequency current having a frequency near the upper limit of speech frequencies, means for passing currents of speech frequency through the receiving coils of said repeaters to modulate the high frequency current and produce a lower sideband within the voice frequency range, and a low

pass filter for suppressing the unmodulated high frequency current and the upper side band.

8. In a secret transmission system, a circuit, means for impressing a current of high frequency near the upper limit of the audio frequency range upon said circuit, a second circuit, means for impressing currents of speech frequency upon said second circuit, an electromagnetic device in said second circuit controlled by said speech currents, means controlled by said device for modulating the high frequency current in said first

circuit in accordance with said speech currents and for preventing the transmission of 15 said speech currents to said first circuit, a third circuit coupled to said first circuit, and means in said third circuit for suppressing the unmodulated high frequency current and the upper side band produced by modulation and for transmitting modulated currents within the audio frequency range. 20

In witness whereof, I hereunto subscribe my name this 19th day of November A. D., 1923.

ROY E. CORAM.
